UNITED STATES PATENT OFFICE.

WANTON C. BARBER, OF VILLISCA, IOWA.

DRILL.

SPECIFICATION forming part of Letters Patent No. 467,459, dated January 19, 1892.

Application filed November 25, 1891. Serial No. 413,029. (No model.)

To all whom it may concern:

Be it known that I, WANTON C. BARBER, of 5
Villisca, in the county of Montgomery and
State of Iowa, have invented a new and use-
ful Improvement in Drills, of which the fol-
lowing is a full, clear, and exact description.

My invention relates to an improvement in
drills, and has for its object to provide a port-
able drill of simple and durable construction
10 and one which is especially adapted for use
in drilling railroad-rails and which is capable
of satisfactory use upon many portions of a
locomotive or upon stationary engines; and,
furthermore, an object of the invention is to
15 construct the drill in a simple, durable, and
economic manner and provide a means whereby
the drill may be readily fed forward or
backward and whereby, also, while the drill
is in operation it will be automatically fed
20 forward while being revolved.

The invention consists in the novel con-
struction and combination of the several parts,
as will be hereinafter fully set forth, and
pointed out in the claims.

25 Reference is to be had to the accompanying
drawings, forming a part of this specification,
in which similar figures of reference indicate
corresponding parts in all the views.

Figure 1 is a central longitudinal section
30 through the drill and its base, the said sec-
tion being taken practically on the line *x x*
of Fig. 3. Fig. 2 is a side elevation of the drill,
and Fig. 3 is a plan view thereof.

The bed or platform 10 of the drill consists,
35 preferably, of a plate of metal on a block of
wood and is usually made rectangular in
general contour. At each side of the bed an
arm 11 is rigidly secured, which arms extend
beyond one end of the bed and are curved
40 upward, terminating in hooks 12, as is best
shown in Figs. 1 and 2, the said hooks being
adapted to clamp the tread of a rail when the
drill is to be used upon the web thereof. The
arms 11 constitute guides for a frame 13, car-
rying the driving mechanism of the drill,

45 which frame is held to loosely slide upon the
bed or platform between the arms, as shown
in Fig. 3. This frame is made rectangular in
general contour and is of skeleton form. The
50 mandrel 14, to which the drill 15 is attached,
is held to loosely turn in that end of the frame
13 facing the hook extremities of the arms 11

and also in cross-bars 16, located near the rear
of the frame, parallel one with the other and
spaced a slight distance apart. That end of the 55
mandrel passing through the cross-bars 16 is
threaded, and upon this threaded portion of
the mandrel a feed-wheel 17 is located, the said
wheel being provided with an aperture to re-
ceive the mandrel, the walls of which aperture 60
are threaded. The feed-wheel partakes some-
what of the nature of a ratchet-wheel and is con-
stantly engaged by a dog 18, which dog is pivot-
ally attached to a crank-shaft 19, journaled in
bearings secured at one side of the frame, the 65
crank-shaft being provided with an upwardly-
extending arm 20, terminating, usually, in a
circular head 21. The dog is maintained in
constant engagement with the feed-wheel
through the medium of a spring 22, as is best 70
shown in Fig. 2. The head or socket 23 of the
mandrel, in which the drill 15 is secured, is
located outside of the frame 13, so that the
drill cannot move laterally inward; but the
drill may be fed laterally outward through 75
the medium of the feed-wheel 17, above re-
ferred to.

A standard 24 is secured at its lower end
in the frame, and upon the upper portion of
this standard the drive-shaft 25 is journaled. 80
This drive-shaft is provided at one end with
a gear 26, adapted to be turned by hand
through the medium of an attached handle
27, and at the opposite end of the drive-shaft
a wheel 28 is secured, the outer side face of 85
which wheel has formed thereon two cam-
surfaces 29 and 30, preferably diametrically
opposite.

The driving-gear 26 meshes with a pinion
31, journaled upon a short shaft within the 90
frame. This pinion has formed upon its in-
ner face a beveled pinion 32, which meshes
with a similar pinion 33, secured upon the
mandrel, and by this means the mandrel is
revolved whenever the driving-gear 26 is 95
turned.

The cam-wheel 28 is adapted to operate the
feed mechanism, and to that end the head 21
of the arm 20, emanating from the crank-shaft
19, is adapted to engage with the side surface 100
of the cam-wheel and travel upon the cam-
surfaces thereof, as is best shown in Figs. 2
and 3. The frame is fed forward through the
medium of a lever 34, fulcrumed upon one of

the arms 11 of the bed or platform and connected with the back of the frame, as is best shown in Fig. 3.

In the operation of the device when the web of a rail is to be drilled, for instance, the hooks 12 of the arms 11 are made to grip the treads of the rail and the frame is fed forward by manipulating the lever 34 until the drill engages with the rail-web. The lever is then held from slipping by engaging with a pin 35, or any other form of locking device may be employed, the said pin being capable of adjustment upon the base. The operation of drilling is then commenced by rotating the drive-shaft 25, whereupon a rotary movement is imparted to the drill-mandrel, and as soon as the arm 20 of the crank-shaft 19 of the feed mechanism engages with a cam-surface of the wheel 28 the arm is forced upward and that portion of the crank-shaft to which the dog is attached is carried inward. Thus the feed-wheel is rotated one or two teeth, according to the distance of the inward throw of the crank-shaft, and the drill-mandrel is thereby revolved in a direction to force its head laterally outward from the frame. By this means it will be observed that while the drill is being turned it is also at proper intervals being fed in direction of the article upon which it is operating.

It is obvious that the device is exceedingly simple and durable, and, further, that it is economic in construction. If in practice it is found desirable, a pad of any description may be placed upon the platform or bed, enabling the operator with comfort to add his weight to the weight of the bed.

Having thus described my invention, I claim as new and desire to secure by Letters Patent—

1. In a drill, the combination, with a bed provided with guides and a shifting-lever, of a frame held to slide upon the bed between the guides and having connection with the shifting-lever, a mandrel held to turn in the frame and adapted to carry a drill, a drive-shaft located above the frame, a driving mechanism connecting the drive-shaft with the drill-mandrel, a feed-device connected with one end of the mandrel, and a connection, substantially as shown and described,

between said device and the drive-shaft, as and for the purpose specified.

2. In a drill, the combination, with a bed provided with guide-arms extending beyond the bed and terminating at their projecting ends in clamps and a shifting-lever fulcrumed upon the bed, of a frame held to slide upon the bed between the guide-arms, a mandrel held to revolve in the frame and adapted to carry a drill, one end of which mandrel is threaded, a feed-wheel having a toothed periphery and a threaded bore and mounted upon the threaded end of the mandrel, a crank-shaft, a dog carried by the crank-shaft and engaging with the feed-wheel, a drive-shaft provided at one end with a driving-gear and at the other end with a cam-faced wheel, a gear connection between the driving-gear and the drill-mandrel, and an arm connected with the crank-shaft of the feed mechanism and having a bearing upon a cam-surface of the cam-wheel, substantially as and for the purpose set forth.

3. In a drill, the combination, with a bed, guide-arms attached to the bed and projected beyond one end, the projecting ends of the guide-arms being formed as hooks, a shifting-lever fulcrumed upon the bed, and a frame held to slide upon the bed and connected with the shifting-lever, of a mandrel adapted to carry a drill journaled in the frame, the head of the mandrel being outside of the frame and its inner end being threaded, a feed-wheel provided with a threaded bore and mounted upon the threaded portion of the mandrel, a crank-shaft journaled at one side of the frame, a spring-pressed pawl carried by the crank-shaft and engaging with the feed-wheel, a drive-shaft, a driving-gear carried by the shaft, a train of gearing connecting said driving-gear with the mandrel, a cam-faced wheel also secured to the drive-shaft, and a connection between the cam-surfaces of this wheel and the crank-shaft, substantially as shown and described.

WANTON C. BARBER.
